APPARATUS FOR APPLYING ABRASIVE TO
BELTS, POLISHING WHEELS, OR THE
LIKEJoseph S. Porter, New Haven, Conn., assignor to
D. & H. Scovil, Incorporated, Higganum, Conn.,
a corporation of Connecticut

Application March 3, 1933, Serial No. 659,541

13 Claims. (CL. 91—18)

In making abrasive wheels or belts it is customary to first apply glue to the surface of the wheel or belt which is to be covered with the abrasive, and then, prior to the drying of the glue, the glued surface is presented to an abrasive in granular form, which is taken up by the glue and will be caused to adhere to the belt or wheel when the glue sets. The character and fineness of the abrasive used depends upon the character 10 of the work for which the belt or wheel is to be employed, and it has been necessary to vary the consistency of the glue, depending upon the fineness of the abrasive.

In the past it has been customary to apply the glue by hand to the element which is to be covered with the abrasive, and in many instances, particularly in the case of wheels, the abrasive itself was applied by hand, in that the wheel was rolled in a trough containing the abrasive. The 15 same method was employed when worn abrasive wheels were recoated with abrasive material. This process was naturally a tedious one as it required considerable time to apply the glue to the surface of the element by hand, and thereafter 20 present it to the abrasive.

In my prior Patent No. 1,775,110, I have shown an apparatus for applying an abrasive to polishing wheels wherein the glue is applied by hand to the abrasive wheel, which is thereafter moved 25 into contact with a traveling belt containing the abrasive. This apparatus was a great improvement over the prior hand methods of performing this operation. The present invention, however, relates to a further improvement, in that, accord- 30

ing to the present method and apparatus for performing it, the application of the glue as well as the application of the abrasive are machine operations and may be carried out with a considerable saving of time and expense.

40 One object of the present invention is to provide a method of covering or recovering a belt or wheel with abrasive such that the operation may be performed speedily, and the abrasive may be applied to the glued surface before the glue has begun to set and while it is in proper condition to take up the abrasive and cause it to adhere tightly.

Another object of the invention is the provision of an apparatus for carrying out the method set forth above.

A still further object of the invention is the provision of an apparatus for supporting a belt or polishing wheel for applying a coat of glue to the surface of the element which is to be covered with abrasive material, and thereafter coat-

ing the glued surface with the desired abrasive, the operations taking place in close sequence and being performed by the apparatus without the necessity of removing the wheel or belt from its support between the operations of gluing and covering.

A still further object of the invention is to provide an apparatus for movably supporting an element to be covered with abrasive, effecting movement of the element beneath a glue dispenser so that it will receive a proper coating of glue upon the entire surface to be covered, and thereafter presenting the glued surface of the element to the abrasive so that all of the operations are performed by the apparatus, and, therefore, performed much more speedily and efficiently than when performed by hand.

Another object of the invention is to provide an apparatus wherein a glue container is arranged in a position spaced from a traveling belt 20 designed to carry the abrasive, and between the container and belt is mounted a support for the element to be covered with abrasive, the support being arranged to move said element across the glue delivery means whereby its surface will be 25 covered with the proper coating of glue and thereafter quickly present it to the abrasive-carrying element so that it will be moved by the latter to cause the abrasive to adhere to the entire glued surface.

To these and other ends, the invention consists in the novel features and combinations of parts to be hereinafter described and claimed.

In the drawings:

Fig. 1 is a front elevational view of an apparatus embodying my improvements and designed to carry out my improved method;

Fig. 1A is a front elevational view of one end of the apparatus, this being a continuation of the view shown in Fig. 1;

Fig. 2 is a sectional view on line 2—2 of Fig. 1;

Fig. 3 is a sectional view on line 3—3 of Fig. 1;

Fig. 4 is a sectional view on line 4—4 of Fig. 1;

Fig. 5 is a partial side elevational view showing the glue container and associated parts;

Fig. 6 is a sectional view on line 6—6 of Fig. 5;

Fig. 7 is a sectional view of the adjusting mechanism for the work support;

Fig. 8 is a sectional view on line 8—8 of Fig. 1;

Fig. 9 is a detail front elevational view of the abrasive container and associated parts; and

Fig. 10 is a sectional view on line 10—10 of Fig. 9.

To illustrate a preferred embodiment of my invention, I have shown a frame 10 in which 55

are mounted pulley shafts 11 and 12 carrying the pulleys 13 and 14, around which is trained an endless belt 15, the belt being maintained in taut position by the idler 16 rotatably mounted upon a shaft 17.

This shaft is carried by two arms 18 pivoted at 19, only one of which arms is shown in the drawings. The shaft may be adjusted to vary the position of the pulley by means of screw rods 20 which are loosely mounted in blocks 21 pivoted on the frame, and which rods are threaded in the ends of the shaft 17. It will be obvious that by turning the rods 20, the shaft 17 will be moved vertically, and by this means the tension of the belt 15 may be properly adjusted.

A motor 22 is mounted on a support 23, the motor being provided with a pulley 24, around which is trained a belt 25. This belt passes around a pulley 26 fixed upon a shaft 27 mounted in bearings upon the frame 10. This shaft, as shown more particularly in Fig. 2, carries a pinion 28 which meshes with a gear 29 secured upon the shaft 11 of the pulley 13. The shaft 11 projects from the frame at the rear side thereof, and a pulley 30 is secured upon its extended end. As shown particularly in Figs. 2 and 3, the frame 10 is open at the top thereof so that the belt 15, as shown in Figs. 2 and 3, travels along this opening so that its upper surface is exposed.

Rising from the rear side of the frame 10 at an intermediate portion thereof are a pair of standards 32 upon which are secured guide plates 33 forming, in connection with the face of the standards, guideways 34 within which is slidably mounted a block or crosshead 35 so that this block is capable of a vertical sliding movement.

As shown more particularly in Fig. 4, the block 35 is provided with a bearing 36 for a shaft 37, which shaft is designed to support the element to which the abrasive is to be applied. If this element be an abrasive wheel, the wheel to be covered is non-rotatably secured to the shaft 37. If, however, it is desired to apply abrasive to a belt, a pulley 38 is secured to the shaft 37 by means of the setscrew 39, as shown particularly in Fig. 4 of the drawings, and the belt 40 to be covered is trained about this pulley.

The shaft 37 is extended rearwardly of the bearing 36, and secured upon its rear end is a gear 41 which meshes with a gear 42 carried by a shaft 43 rotatably mounted in a block 44 secured to the sleeve of the bearing 36. Also secured to the shaft 43 is a pulley 45, and a belt 46 is trained about this pulley and also passes about the pulley 30 upon the shaft 11, as shown in Fig. 2. It will be observed, therefore, that the shaft 27 is rotated by the motor 22 and in turn drives the shaft 11, the pulley 13, and also the pulley 30, and through the belt 46 drives the pulley 45, the gears 42 and 41, and the shaft 37 and pulley 38, provided that the block or crosshead 35 is raised to a sufficient height to hold the belt 46 taut.

A rockshaft 48 is mounted in bearings in the side walls of the frame 10, this rockshaft having secured thereto a crank 49 connected by a link 50 to the block 35, so that when the shaft 48 is rocked, this block may be raised and lowered in the ways 34. The raising and lowering of this block serves to raise or lower the shaft 37 and pulley 38 fixed thereon, so that the belt 46 to be covered by the abrasive may be lowered into contact with the belt 15 or raised out of contact with this belt.

As shown more particularly in Figs. 1, 2, 3 and 7, levers 51 and 52 are provided for rocking the shaft 48, the former being designed to impart a sudden or abrupt movement to the shaft and the block 35, and the latter being designed to impart a slow or adjusting movement to the shaft and block. To effect this result, the shaft 48 is rotatably mounted at one end upon a shaft 53 which is rotatably mounted in a sleeve 54, which in turn is rotatably mounted in a bearing 55 in the side wall of the standard 10. Lever 51 is secured to the sleeve 54, while lever 52 is secured upon the shaft 53.

Secured to the sleeve 54 is a collar 56 carrying a shaft 57, upon which is rotatably mounted a double gear having gear teeth 58 and 59. Gear 58 is in mesh with a gear 60 secured to the shaft 48, while gear 59 is in mesh with a pinion 61 secured to the shaft 53. Also secured to shaft 53 is an arm 62 from which projects a pin 63 engaging a brake band 64 which encircles a brake drum or pulley 65 secured on the shaft 48.

It will be obvious that when the lever 52 is moved, the shaft 53 is rotated, which turns the gear 61 keyed upon this shaft. This gear in turn effects rotation of the gears 58 and 59, the latter effecting rotation of the gear 60 and thereby moving the shaft 48. As the gears 61, 58, 59 and 60 constitute a reducing gear train, it will be seen that the shaft 48 is moved through a smaller angle than the lever 52, and hence a slow speed action of the shaft 48 is effected, which in turn results in a slow or adjusting movement of the crank 49 and the block 35. During this movement the brake band 64 is moved by means of the arm 62 secured upon the shaft 53, but as the brake is only frictionally engaged with the brake drum or pulley 65, it will during this operation move or slip over the surface of this drum.

When the lever 51 is moved, the sleeve 54 will be rotated and through it the collar 56 which will tend to cause the gears 58 and 59 to revolve about the gears 60 and 61. The resistance of the brake is, however, sufficient to prevent such movement, and as a result the entire train of gearing will move as a unit, thus effecting rotation of the shaft 48 at exactly the same speed as the sleeve 54. In other words, this results in a direct movement of the shaft 48 by the lever 51 which effects an abrupt movement of the crank 49 and crosshead 35. Thus, it will be seen that a slow and fast movement of the block 35 is provided.

A spring 67 is supported at one end by a bracket 68 on the frame 10, and at its other end this spring rests upon a cam roller 69 eccentrically mounted on a shaft 70 rotatably carried by the frame 10 and rotated by a crank handle 71. This crank handle carries a pin 71a which may be engaged in openings 71b of the frame 10 to hold the crank handle in adjusted position. Upon an intermediate portion of this spring is carried a block 72 having a backing roller 73 rotatably mounted therein. This backing roller lies below, and is designed to support, the belt 15 at the point of contact of the wheel or belt which is to be covered by the abrasive. In other words, when the wheel or belt to be covered is lowered into contact with the belt 15, this contact will lie above, and the pressure be resisted by, the roller 73 carried upon the spring 67. The crank 70 71 may be rotated to turn the cam roller 69 and properly adjust the tension of this spring so that the necessary resistance will be offered by the roller 73.

As shown in Fig. 1, an abrasive container 74 is

mounted above the standard 10 and above the run of the belt 15 so that abrasive may drop from this container directly upon the upper surface of the belt. The outlet 75 of this container is controlled by a gate 76 slidably mounted upon the

5 mounted in the standards 32 and rockable by a lever 95. It will be apparent that movement of this lever will serve to raise or lower the rack bars 92.

10 trolled by a gate 76 slidably mounted upon the container, the gate being held against the outlet opening by means of springs 77 mounted upon screws 78 fixed in the gate and passing through eyes 79 upon the container. The throw of the gate may be varied by means of an adjusting screw 80 mounted in the gate and designed to contact with a fixed stop 81 on the container. The gate is operated by rock arms 82 connected at each side thereof, which arms are secured to a 15 shaft 83 rockably mounted on the frame and having secured thereto at one end a friction disk 84, shown more especially in Fig. 10. A clamping disk 85 is loosely mounted upon this shaft, and between the disks 84 and 85 is a third disk 86 having an arm 87 depending therefrom. It will be understood that the disk 86 is clamped frictionally between the disks 84 and 85, so that while turning of the disk 86 will normally effect movement of the disk 84 and shaft 83, the disk 86 may 20 25 slip by the disk 84 when the shaft 83 encounters resistance to its movement.

25 The arm 87 is pivoted at its lower end to a link 88, which in turn is pivoted at its lower end to an arm 89 secured to the collar 56. It will be recalled that this collar is moved by the lever 51 so that when this lever is moved in one direction, for example, the direction to move the block 35 downwardly to present the element to be covered by abrasive to the belt 15, the arm 87 will be moved in a direction to turn the shaft 83, to raise the gate 76, to uncover the container outlet and allow abrasive to run from the container upon the surface of the belt 15. This movement will take place immediately upon the movement of the lever 51 so that the outlet opening will be uncovered to its fullest extent, determined by the adjusting of the screw 88. When this screw strikes the stop 81, any further movement of the arm 87 will be ineffective as the rockshaft 83 will be prevented from turning and the disk 86 will slip upon the disk 84. Upon the return movement of the lever 51 in a position to raise the block 35, the initial part of this movement will effect the closing of the outlet opening of the container, as the disk 86 will effect movement of the disk 84 and shaft 83. When the gate has been dropped, however, the disk 86 will slip upon the disk 84 and the lever 51 will be permitted to return to its original position without further movement of the gate 76. It will be obvious, therefore, that this provides in effect a lost motion connection between the lever 51 and the gate 76, whereby the gate will be moved at once to full open and closed positions upon the initial movement of the lever 51, and the lever will, thereafter, be permitted to move without having any effect upon the gate. By this means the supply of abrasive is always adequate whenever the element to be covered is lowered into contact with the belt 15, and, likewise, the flow of abrasive will be completely shut off when the covered element is raised from contact with the belt 15.

70 A chute 89 is mounted on the frame 10 adjacent the pulley 14 to convey excess abrasive material dropping from the belt 15 to a suitable container (not shown).

75 A pair of rack bars 90 and 91 are slidably mounted in the standards 32, these members having rack teeth 92 thereon which are engaged by pinions 93 secured upon a shaft 94 rotatably

Secured to the upper end of these bars is a frame 96 which projects in a horizontal direction, and supported on this frame is a rod 97 and a bar 98, the rod and bar projecting forwardly so as to overlie the top of the frame 10. Slidably supported upon this rod and bar is a 10 plate 99, this plate being rounded at one end, as shown at 100, so as to embrace the rod 97. Secured to the plate 99 is a glue pot or container 101 having a glue compartment 102 and a jacket 103 which may contain a liquid, such as water, 15 to be heated so as to keep the glue in a liquid condition. Below the water jacket 103 the base of the container is provided with an opening 104 in which a suitable electric heating element may be inserted to keep the water at the proper temperature. Leading downwardly from the container 102 is a discharge passage 105 in which is mounted a rotary valve 106 which may be operated by the handle 107. Below this valve the passage 105 is reduced in size, and across its 20 25 mouth is mounted a plate 108 containing either a narrow slot or a row of openings to permit the egress of the glue when the valve 106 is in the proper position. This plate is dovetailed or beveled at its edges and rests in a cutaway portion 30 of the base of the container, the edge of which is beveled at one side. At the other side a pair of arms 108^a are secured to the base by screws 108^b and bear against the dovetailed edge of the plate to hold it in place and provide for its ready 35 removal.

It will be apparent that the glue container secured to the plate 99 may, when not in use, be positioned rearwardly of the apparatus, as shown, for example, in Fig. 2. When it is desired to operate the machine to coat the work with glue, the handle 107 may be grasped and the glue container drawn outwardly on its supports 97 and 98 to the position shown in Fig. 5, where the discharge opening in the plate 108 overlies the work. 40 45 The handle 107 may then be turned to open the valve when the operator is ready and allow the glue to flow upon the work.

It has already been stated that my apparatus may be used to coat either wheels or endless 50 belts with abrasive, the work-supporting shaft or spindle 37 being designed either to receive the abrasive wheel, or, as shown in the drawings, to receive a pulley 38 to carry the endless belt. When abrasive wheels are being covered or recovered, it is only necessary to secure this wheel to the spindle 37, no cooperating means being required. When, however, as shown in the drawings, the work to be covered consists of an endless belt, I secure to the bearing 36, an arm 110 55 60 to support an idler pulley 111 over which the work or endless belt 40 is adapted to run. This pulley is provided with flanged sides, as shown at 112, so as to keep the work properly aligned with the outlet opening of the glue container. 65

In order to support the other end of the belt, a horizontally disposed frame 113 is secured to the frame 10, and slidably supported upon the frame 113 is a standard 114 carrying a pulley 115 around which the belt 40 is trained. Connected 70 to the standard 114 is a rod 116 secured at its other end to a lever 117, to which is secured a rod 118 connected to a manually operable lever 119. It will be seen that movement of the rod 118 to the left, as shown in Fig. 1, tends to move the 75

standard 114 to the right and tighten the belt. The lever 119 may be engaged with one of a series of rack teeth 120 to hold the standard 114 in the desired position.

5 While the operation of the device will be apparent from the foregoing description, it may be briefly described, as follows:

If it is desired to cover or recover an endless belt with abrasive material, the belt will be 10 mounted upon the work-supporting pulley 38 and the idler pulley 115 and trained over the flanged roller 111. It will, of course, be understood that the desired abrasive has been placed in the abrasive container 74 and that the glue container 15 contains a sufficient quantity of glue which is of the proper consistency and at the proper temperature to be applied to the belt. The glue container is then drawn outwardly over the belt from the 20 position shown in Fig. 2 to that shown in Fig. 5, and the lever 51 is moved to the left, as shown in Fig. 1 to raise the block 35 and work-carrying spindle 37 to its upper position. The work, which in this instance is an endless belt, during the application of the glue thereto travels with its upper 25 surface in close proximity to the plate 108. If this is not the case when the lever 51 has been moved to the left, the adjusting lever 52 may be operated to effect a slow adjustment of the block 35 until the work is in proper relation to the glue 30 discharge opening in the plate 108. This adjustment will, of course, be found particularly desirable in the case of covering abrasive wheels wherein wheels of different diameters are encountered, and, hence, need adjustment so that their 35 surfaces will be in proper relation to the glue discharge outlet.

It will be understood that when the block 35 and work-carrying spindle are raised to their upper positions, as has just been explained, the 40 belt 46 is rendered taut inasmuch as the pulley 45 is drawn upwardly with relation to the pulley 30. The motor is now put into operation with the result that rollers 13 and 14 are rotated to move the abrasive carrier belt 15, and likewise the 45 pulley 38 is rotated to effect travel of the work or endless belt 40. The lever 51 being moved to the left, as shown in Fig. 1, the gate 16 of the abrasive container is in its lower closed position.

With the work in motion, the handle 107 is 50 stated to move the valve 106 to open position and allow the glue to flow from the container upon the work. The glue will be properly spread in a thin and even coating upon the work by the plate 108, and the operation is continued until the entire 55 surface of the work has been covered. As this plate spreads the glue in an even and thin coat, and, moreover, does it so rapidly that the work will be completely coated before the glue has begun to set, there will be no "lap" or any thick 60 coat of glue upon that portion of the work which may pass under the discharge outlet a second time. When this occurs, the coat of glue is simply spread out to its original thickness.

When the work has been completely covered 65 with glue, the lever 51 is moved to the right to drop the work-carrying spindle 37 so that the work comes in contact with the upper surface of the belt 15. This contact will be at a point above the backing roller 73 so that the pressure of the work upon the belt will be resisted by this roller and the proper amount of pressure applied to cause the abrasive to be taken up by the glue to 70 make an even coat. It will be understood that the belt 15 has been moving while the work is being 75 coated with glue, but as the work is not in con-

tact with the belt, and as the belt is carrying no abrasive at this time, the belt 15 will merely be running idly. When, however, the lever 51 is moved to the right to lower the work upon the belt 15, the gate 16 will be opened to allow the abrasive to flow from the container 74 upon the surface of the belt in a relatively wide but thin stream. When the work-carrying spindle 37 and block 35 is lowered, the belt 46 will no longer be taut, and the pulley will not be driven by this 10 belt. Immediately, however, the work comes in contact with the belt 15 it will be driven by this belt at the same speed as the belt, so that during the process of covering the glued surface with the abrasive material, the work will no longer 15 be driven positively but will merely be driven by contact with the abrasive-carrying belt.

I have ascertained that while it is advantageous to drive the work at the same speed as the abrasive-carrying belt during the operation of 20 covering the glued surface with the abrasive material, it is also desirable to drive the work during the gluing operation at a higher speed than during the covering operation. This result is accomplished in a simple and expedient 25 manner by my apparatus in that the work, when driven positively during the gluing operation, may, of course, be operated at any desired speed, and at the same time, when the work-carrying spindle is in its lower position, the positive drive 30 is automatically stopped and the work thereafter driven at the same surface speed as the abrasive carrier.

When the work has been completely covered with abrasive material, the motor is stopped and 35 the work removed, and it may be placed in a suitable apparatus for drying. If desired, a second coat may later be applied.

The operation of the device when used to cover or recover an abrasive wheel is substantially the 40 same as that described in case of a belt, as the wheel to be covered is merely secured to the work-carrying spindle 37 in place of the pulley 38. It will be found that with my apparatus, a 45 coat of glue of uniform thickness may be applied to the work in a much shorter time than may be done by hand. Likewise, the coating of abrasive material may be applied to the work more quickly and more evenly than was formerly possible, and, moreover, the coating of abrasive 50 will be of uniform thickness and its density may be regulated by the pressure of the work upon the belt 15 as determined by the backing roller 73 and the lever 51.

Difficulty has been experienced in the past 55 particularly in coating endless belts where the gluing operation has been done by hand, in that, particularly in the case with relatively long belts, the glue will begin to set before the operation has been completed, and, hence, there is 60 an objectionable "lap" at the point of the beginning and ending of the operation. Moreover, it has been impossible to satisfactorily glue relatively thin and cheap belts by hand, possibly owing to the difficulty of securing an even 65 and uniform coat, which is secured by the use of my apparatus.

It has also been the custom to vary the consistency or thickness of the glue according to the size of grain of the abrasive used. I am, 70 however, able with my apparatus to use the same glue for coarse or fine abrasive, within wide limits. Regardless of the consistency of the glue, I am able to secure a uniform and even coat of 75 the proper thickness over the entire surface of

the work. The thickness of the coat of adhesive will be determined in general by the amount of clearance between the work and the plate 108.

The frame 96 is provided with a water pan 125 which, in this instance, is formed integrally with the frame, which pan may contain the proper amount of water or other suitable liquid which will tend to keep the glue or other adhesive soft when the machine is not in operation. As shown in Fig. 5, the bar 98 is provided with a raised surface 126 intermediate its length, this raised surface being joined to the remainder of the bar by inclined surfaces 127 and 128. When the container 101 is moved to the right from its position, shown in Fig. 5, the plate 99 upon which it is supported will ride upwardly over the surface 126 so that the plate 108 will be carried over the frame 96 or over the edge of the pan 125. Thereafter the plate 99 will ride downwardly over the surface 128 so that the glue discharge opening through the plate 108 will be immersed in the water in the water pan 125 and keep the glue in the discharge opening below the valve 106 in a soft condition.

25 In the covering of abrasive wheels, it is very often the custom to put two or three applications of abrasive to the wheel before it is ready for use, as sufficient abrasive cannot be put on at one time. It is usual to apply one coat to the wheel and permit it to dry for a half hour or so, so that the adhesive will set to a certain extent before applying the following coat of adhesive and abrasive. If a third coat is to be applied, another interval is required following the second coat before the application of the third. I have found that when the abrasive is applied by machinery instead of by hand, it is possible to apply a second coat immediately after the first, and a third immediately after the second without waiting for the preceding coat to set, and, of course, without removing the wheel from the wheel support. When the adhesive is applied by my machine, it is flowed upon the work instead of being brushed thereon, as is the case with hand application. It, therefore, does not disturb the preceding coat, even when applied immediately. This is one decided advantage of my method and machine, in that several coats of adhesive and abrasive may be applied to a wheel successively without removing it from the machine, which will result in a considerable saving of time and expense.

50 While I have shown and described a preferred embodiment of my invention, it will be understood that it is not to be limited to all of the details shown, but is capable of modification and variation within the spirit of the invention and within the scope of the appended claims.

What I claim is:

1. In an apparatus of the character described, a suitably supported adhesive container having a delivery outlet, a work-supporting member for supporting the surface of the work below said delivery outlet to receive adhesive therefrom, means for moving the work while so supported, an abrasive carrier mounted below the work support, means for delivering a supply of abrasive to said carrier, and means for moving said work support to present the work to said carrier to apply a coat of abrasive thereto.

2. In an apparatus of the character described, a suitably supported adhesive container having a delivery outlet, a work-supporting member for supporting the surface of the work below said delivery outlet to receive adhesive therefrom, means

even uniform coat, means for moving the work while so supported, an abrasive carrier mounted below the work support, means for delivering a supply of abrasive to said carrier, and means for moving said work support to present the work to said carrier to apply a coat of abrasive thereto.

3. In an apparatus of the character described, an endless belt, mechanism for imparting movement to the belt, means for depositing abrasive on the upper surface of the belt, a rotatable work-holding spindle adapted to be moved toward and from the upper surface of the belt, means for applying a coat of adhesive to the work when supported on said spindle, and means for adjusting the spindle to bring the surface of the work in substantial contact with said adhesive-applying means.

4. In an apparatus of the character described, a work-supporting member, means for effecting movement of the work when supported on said member, means for applying a coat of adhesive to the moving work, means for delivering a supply of abrasive to the adhesive-covered surface of the work without removing the latter from said support, and means for adjusting the surface of the work relative to said adhesive-applying means to control the thickness of the coat of adhesive applied thereto.

5. A machine for applying abrasive to wheels, belts, or the like, comprising a suitably supported adhesive container having a delivery outlet, a traveling belt positioned below said outlet and spaced therefrom, an abrasive container mounted in position to deliver abrasive upon said belt, a work-supporting spindle mounted above said belt, means for raising and lowering said work spindle to bring the work into and out of contact with the belt, and means actuated by said raising and lowering means to control the delivery of abrasive to said belt.

6. A machine for applying abrasive to wheels, belts, or the like, comprising a suitably supported adhesive container having a delivery outlet, a traveling belt positioned below said outlet and spaced therefrom, an abrasive container mounted in position to deliver abrasive upon said belt, a work-supporting spindle mounted above said belt, means for raising and lowering said work spindle to bring the work into and out of contact with the belt, and means actuated by said raising and lowering means to control the delivery of abrasive to said belt, said last-named means having a sliding connection with said raising and lowering means.

7. A machine for applying a coat of abrasive to abrasive wheels, endless belts, or the like, comprising an endless belt, mechanism for imparting movement to said belt, means for depositing abrasive on the upper surface of the belt, a work-holding spindle supported above the belt and adapted to be moved toward and from the same, means to move said spindle toward said belt to cause the work to contact with the belt under pressure and means to regulate said pressure.

8. In a machine of the character described, a suitably supported abrasive carrier, means for delivering a supply of abrasive to said carrier, a glue container supported above the carrier, a work spindle movably supported above the carrier and adapted to support the work below said glue container, means to move said spindle toward the glue container to present the work thereto and to move the spindle toward the abrasive carrier to effect contact of the work therewith under pressure, and spring-pressed means below said abrasive carrier opposite the point of

contact of the work therewith to resist such pressure.

9. Means for applying abrasive to an endless belt comprising a suitable supporting frame, a pair of pulleys rotatably mounted on the frame about which the belt to be covered is adapted to be trained, means for driving one of said pulleys, adhesive delivering means arranged above said driven pulley to deliver a coat of glue upon the belt thereon, an abrasive carrier below the belt, and means to lower one of said pulleys to effect contact of the belt with said abrasive carrier.

10. An apparatus for applying a coat of abrasive to an endless belt comprising suitably supported pulleys for supporting the belt, means for driving one of said pulleys to effect travel of the belt, means for spreading a coat of glue upon the surface of the belt while so supported, an abrasive carrier adjacent the belt, and means for moving the belt in contact with said carrier to apply a coat of abrasive to the glued belt.

11. In an apparatus of the character described, a suitably supported adhesive container having a delivery outlet, a work-supporting member for supporting the surface of the work below said delivery outlet to receive adhesive therefrom, means for driving the work when supported on said mem-

ber, an abrasive carrier mounted below the work support, means for moving said work support to present the work to said carrier to apply a coat of abrasive thereto, and means for releasing the work from its driving means when the work support is moved to present the work to said carrier.

12. Means for covering endless belts or abrasive wheels with adhesive and covering the adhesive-coated work with an abrasive comprising an adhesive-applying means, an abrasive carrier, a support for the work movably mounted between said adhesive-applying means and the abrasive carrier, and said adhesive-applying means being movable toward and from the work support for the purpose described.

13. Means for applying a coat of abrasive to an endless belt comprising a plurality of supporting pulleys for the belt, an abrasive carrier comprising an endless belt, means for imparting movement to said carrier belt, means for depositing abrasive material on the upper surface of the carrier belt, and means for moving one of the supporting pulleys to cause said belts to travel in contact with each other to cover the first-named belt with the abrasive material.

JOSEPH S. PORTER.
